UNITED STATES PATENT OFFICE.

MARTIN L. HEINEKE, OF SPRINGFIELD, ILLINOIS.

JACK.

Application filed May 12, 1924. Serial No. 712,567.

To all whom it may concern:

Be it known that I, MARTIN L. HEINEKE, a citizen of the United States, residing at Springfield, county of Sangamon, and State 5 of Illinois, have invented new and useful Improvements in Jacks, of which the following is a specification.

This invention relates to improvements in jacks. More specifically, this invention relates to wheeled jacks of the type adapted 10 for garage use.

It is the primary object of this invention to provide a novel and improved jack of the distant control type, wherein each forward 15 and each back stroke of the handle will serve to elevate or lower a lifting member at a distance therefrom. In many jacks of this general type which have heretofore been designed the arrangement has been such that 20 the handle operates to lift or lower the jack member only when it is moved in one direction. The return stroke of the handle accomplishes no useful purpose, and consequently, the mechanical advantage of such 25 a jack, considering every handle movement, is comparatively low. It has been my purpose in developing the jack disclosed herein to provide a construction such that despite the distance between the handle and the jack 30 member there will nevertheless be provided means for utilizing every movement of the 35 handle for actively lifting or lowering the load. Thus, I am able to lift a load with my improved jack in less time, with less effort, with fewer strokes, and with greater 40 mechanical advantage than is possible in a jack where a uni-directional stroke is operative for lifting purposes.

It will be understood by those skilled in 45 the art that in the type of jack to which this invention particularly relates, i. e., in a jack in which the lifting member or plunger is located at one end of an elongated frame and the handle is located at a distant point on said frame, it is comparatively difficult to work out what may be termed a double acting jack movement. It would be less difficult merely to provide a double acting jack of this type to move the load in one direction only, but it is my purpose in 50 the present invention to provide means for utilizing every stroke of the jack handle to move the load, whether the jack is adjusted for lifting or for lowering. Consequently,

it is an important feature of this invention 55 to provide simple, effective and novel means for controlling the movements of the load carrying element so that upon the oscillation of the jack handle the load carrying element may readily be caused either to lift 60 or to lower the weight carried thereby as the operator may desire.

While it is my broad purpose to provide a double acting jack as aforesaid, it is also my purpose to provide an improved set of 65 motion transmitting connections between an oscillatory jack handle and a load lifting element. Such motion transmitting connections as those hereinafter to be disclosed are adapted for use in single acting jacks 70 as well as in double acting jacks, and consequently, I will hereinafter disclose the application of these motion transmitting connections to both types of jack.

Other objects of this invention are to provide an unusually sturdy and simple type of jack mechanism having comparatively few parts; to provide a jack with novel and simplified means for obtaining a preliminary 75 adjustment of the load carrying element; to provide a jack which can be easily and cheaply manufactured and readily operated by unskilled persons without danger either to the jack or to the vehicles manipulated 80 therewith.

In the drawings:

Figure 1 is a plan view of the jack embodying this invention, the jack frame being foreshortened and the handle cut away.

Figure 2 is a side elevation of the device 90 shown in Figure 1, with the side of the jack frame partially removed to expose the motion transmitting connections.

Figure 3 is an enlarged detail view taken on the section indicated at 3—3 in Figure 2.

Figure 4 is a detail view of portions of the motion transmitting connections shown in Figure 2, illustrating the parts in one position which they will assume when the 100 jack is in operation.

Figure 5 is a view similar to Figure 4, showing the same parts in different relative positions.

Figure 6 is a further view similar to Figure 4, showing the parts in a further set of relative positions.

Figure 7 is a fragmentary plan view of a

single acting jack embodying portions of this invention.

Figure 8 is a detail view in side elevation of the motion transmitting mechanism shown in plan in Figure 7.

Figure 9 is a view similar to Figure 8, showing some of the same parts in different relative positions.

Figure 10 is a further view similar to Figure 8 and showing some of the same parts in further different relative positions.

Like parts are identified by the same reference characters throughout the several views.

15 The jack frame includes a cylinder casting 10 in which is vertically movable a plunger or load carrying element 11 having a telescopically adjustable portion 12 with a load carrying head 13. The cylinder casting 10 may be supported in any desired manner but is preferably provided integrally with an axle 14 offset forwardly from it and supporting it from wheels 15.

It is the function of member 12 merely to 25 provide for a preliminary adjustment in height of the load carrying element. For this purpose the member 12 is preferably peripherally grooved as at 18. In order adjustably to support telescopic member 12 with reference to the main plunger or load carrying element 11, I may utilize a box 19 connected with member 11 and containing a slide 20 having an arcuate notch adapting it to fit about the reduced diameter of member 12 within one of the peripheral grooves 18 of said member. Thereby the telescopically adjustable parts 11 and 12 are maintained positively at the desired position of adjustment and, at the same time, the member 12 is free to rotate upon the supporting slide 20.

When it is desired to change the adjustment of these parts the operator may grasp the head of a rod 22 connected with a slide 20 and may thereby retract the slide against the compression of spring 23. As soon as the slide clears groove 18 it will be possible to lift or lower member 12 manually with respect to member 11. When, however, the head 21 is released by the operator, the slide 20 will again be forced by spring 23 into one of the peripheral grooves 18 of member 12 to restrict members 11 and 12 against relative vertical movement in any position of adjustment of these members so that they are operated as one by the lifting and lowering mechanism hereinafter to be described. In the lifting and lowering of the plunger or load carrying element 11, the said element is guided within the cylinder 10. It preferably has a rather close fit in the cylinder. For a similar purpose the ungrooved portions of member 12 will also preferably have a rather close fit within the hollow piston or load carrying element.

Connected with the cylinder casting 10 65 and extending rearwardly therefrom are laterally spaced parallel bars 25 and 26. These bars comprise the frame of the machine but it is immaterial to this invention whether or not the elongated frame be constructed in 70 the specific manner herein disclosed. The rear end of the frame is supported by a caster wheel 27 in order that it may be readily manipulated from side to side under load. Immediately above the caster wheel 27 is an 75 upwardly extending handle 30 which is oscillatory on bolt 28 as a fulcrum, whereby to serve as a lever for the lifting and lowering of loads. The handle serves also to enable the operator readily to manipulate the entire 80 jack upon its wheels 15 and 27.

A connecting rod 31 is pivoted to the handle 30 at 32 and extends forwardly therefrom between the parallel sides 25 and 26 of the frame. The connecting rod is made fast 85 at its forward end to a slide 34 which is slotted at 35 for guidance upon a transverse shaft 36. Upon this shaft is mounted a toothed wheel 37 to which is pivoted at 38 a link 39, the other end of which is pivotally 90 connected at 40 with the load carrying element 11. The link may conveniently be double, as is best shown in Figures 1 and 3, to engage each end of pin 40. Pin 40 intermediate the two link members 39 passes through 95 an ear 41 projecting laterally from the member 11 which it actuates. Obviously, if the toothed wheel 37 be rotated clockwise from the position in which it is illustrated in Figure 2, its movement will be transmitted 100 through links 39 to the load carrying element to elevate said element. Conversely, a counter-clockwise rotation of the toothed wheel 37 toward the position in which it appears in Figure 2 will lower the load carrying element.

Means will now be described for utilizing reciprocating movement of connecting rod 31 and slide 34 to control the rotative movement of the toothed wheel 37.

For the purpose of securing such control the slide 34 carries a pair of dogs 43 and 44 which are pivoted thereto at 45 and 46, respectively. These dogs are provided with pointed extremities engageable with the 115 teeth of wheel 37. The extremity 47 of dog 43 is in the form of a hook and engages the teeth of wheel 37 in the manner of a hook. The extremity 48 of dog 44 is formed like a finger and engages the wheel 37 with a pushing action. Consequently, dogs 43 and 44 will hereinafter be termed, respectively, tension and compression dogs.

Since each of the aforementioned dogs is pivoted within the central slot of slide 34, it 125 will be obvious that as such slide is reciprocated by the oscillation of handle 30 the dogs 43 and 44 will be reciprocated therewith.

In the course of such reciprocation the dogs will be caused to move to and fro with respect to the teeth of wheel 37 and, if the dogs continuously follow the contours of such teeth, their reciprocation will obviously result in producing a clockwise rotation of wheel 37 to produce a lifting movement of the load carrying element 11. To ensure that the dogs will thus follow the contours 10 of the teeth when desired I provide a compression spring 49 confined between the rear extremities of dogs 43 and 44 to force such extremities apart and thereby to keep the forward ends 47 and 48 of the dogs in contact with the wheel, except at such times as other means hereinafter to be described are acting upon the dogs.

It will be observed from the foregoing that the lifting operation of the jack is accomplished by a substantially pure ratchet and pawl movement. When, for example, handle 30 is oscillated counter-clockwise the connecting rod 31 and slide 34 will be reciprocated to the right as viewed in Figure 2. Thereupon the point 47 of dog 43 will pull rearwardly upon the tooth of wheel 37 with which it is engaged, thereby causing the said wheel to rotate clockwise. At the same time the point 48 of dog 44, in moving rearwardly, will ride over the tooth which it abuts and will engage behind said tooth to support the wheel 37 against counter-clockwise rotation.

As handle 30 reaches the extremity of its oscillatory stroke and is moved clockwise, the slide 34 will have a corresponding movement to the left, as viewed in Figure 2. Hook-shaped extremity 47 of pawl 43 will ride over a tooth of wheel 37 while the fingerlike end 48 of pawl 44 is engaged with a tooth on the lower side of said wheel and, due to its engagement therewith, is pushing the said tooth to the left and continuing the clockwise rotation of the wheel.

When it is desired to lower the load carrying element a special pawl-controlling mechanism is brought into service. This mechanism is adjusted in any desired manner, such for example, as by the provision of a lever 50 on the jack frame. This lever is carried by a short shaft 51 extending transversely through the side member 26 of the frame, and carrying on its inner end a crank arm and crank pin 52. A link 53 connects the crank pin with a cross head 54 slidable upon the frame member 26 longitudinally of the frame. Arms 55 and 56 pivoted to the cross head 54 externally of the frame member 26 carry pins 57 and 58, respectively, which ride on the upper and lower margins of frame member 26 or are otherwise longitudinally guided with reference to said frame member. A tension spring 59 connecting arms 55 and 56 keeps the pins 57 and 58 normally in contact with

the margins of the frame member 26. The length of pins 57 and 58 is such that they project into the tooth of the rearward extremities 60 and 61 of dogs 43 and 44, respectively.

The handle 50 has an oscillatory movement on the axis of the shaft 51 and is limited in such movement by stops 62 and 63 carried by the frame element 26. With the handle 50 in the position in which it is illustrated in Figure 2 (in contact with stop 62) the cross head 54 is in its extreme position to the right, and the arms 55 and 56 have been retracted to such a point that the pins 57 and 58 are not operative with respect to dogs 43 and 44. In this position the dogs will operate as pawls to elevate the load carrying element 11 in the manner already described. If, however, the handle 50 be oscillated to the position in which it appears in Figure 1, the cross head 54 will move to an extreme position at the left and the pins 57 and 58 will be moved into operative association with the peculiarly formed cam surfaces at the rear extremities 60 and 61 of dogs 43 and 44.

In the above described relation of the parts every oscillatory movement of handle 30 will result in lowering the load carrying element of the jack. In Figure 4 the parts are shown as they appear when the handle 30 is oscillated forwardly to retract slide 34, and the dogs 43 and 44 carried thereby. The strength of tension spring 59 is understood to be such as to overcome the strength of compression spring 49. Inasmuch, however, as the pin 57 is engaged in the lowest part of the cam-like depression in the rear extremity of dog 43, it will be obvious that the compression of spring 49 will be freely exerted to maintain the hook portion 47 of dog 43 by engagement with a tooth of wheel 37. Pin 58, on the other hand, will have ridden onto a relatively high portion of the cam surface of dog 44 and will thereby have forced the said dog outwardly away from the teeth of wheel 37.

As the handle 30 moves rearwardly the parts will assume the positions illustrated in Figure 5, wherein the relatively stationary pin 57 is riding onto the elevated cam surface of dog 43. At the same time, pin 58 has, due to the forward movement of dog 44, passed downwardly from the high portion of the cam surface on said dog and is permitting said dog to be forced by the compression of spring 49 into engagement with a next succeeding tooth on wheel 37. As the rearward movement of the handle continues, the parts reach the position in which they are shown in Figure 6, wherein the finger portion 48 of dog 44 is in full engagement with the next succeeding tooth of wheel 37, and the hook portion 47, having cleared the point of the tooth which it

abutted in Figure 4, is now in position to move downwardly along the rear side of said tooth into engagement with the next succeeding tooth of the series. Figure 6 shows 5 the ultimate position of the parts during the rearward movement of the handle. Thereupon, as the handle is oscillated forwardly slide 34 and dogs 43 and 44 are moved rearwardly, the dog 44 carrying the load until 10 dog 43 reaches the next succeeding tooth in a position corresponding to that of Figure 4 and picks up the load. During this rearward movement of the parts the finger portion 48 is held by the load in engagement 15 between two adjacent teeth of wheel 37 despite the action of pin 58, which tends to force the dog outwardly to the Figure 4 position thereof. Consequently, the pin 58 is forced to yield on arm 56 against the 20 tension of spring 59. As long, however, as the hook portion 47 of dog 43 takes up the load as shown in Figure 4 the said dog 44 springs outwardly to its Figure 4 position and, due to the cam action of pin 58 upon 25 it (it will, during the next rearward oscillation of the handle, pass over the tooth which it has previously supported and will engage the next succeeding tooth. This action is continued until dog 44 reaches the 30 last tooth of the series with which wheel 37 is provided, or until handle 50 is oscillated to retract cross head 54 and the pins 57 and 58 connected therewith.

Figures 7 to 10 illustrate a single acting 35 jack in which the jack lever is operative in but one direction of movement to lift or to lower the load supporting element. These views show the parts from the opposite side from which they were disclosed in the preceding views. The frame members 25 and 40 26 may correspond exactly with views previously described. So also the cylinder casting 10 and load carrying element 11 may correspond with the similar parts on the 45 double acting jack. The load carrying element 11 is preferably connected with the toothed wheel 37 by the same type of link 39 used in the jack previously described.

In the single acting jack, however, there 50 is but one reciprocable dog. This dog is carried by a slide 34' connected by rod 31 with the handle, whereby it may be caused to reciprocate. The single dog 43 which is carried by slide 34' is preferably substantially 55 identical with that already described. The other dog comprises purely a pawl 65 having a finger portion 48' and an arm 66 projecting rearwardly beyond its cam surface 61'. The arm 66 receives the pressure of 60 a relatively fixed compression spring 67 whereby the finger portion 48' of the pawl 65 is normally maintained in contact with wheel 37. With the parts as shown in Figure 10, the jack is set for a lifting operation, and 65 upon each oscillation of the controlling han-

dle 30, as previously described, the slide 34' will be caused to reciprocate and the single dog 43 carried thereby will alternately engage one of the teeth of wheel 37 on its rearward stroke and will ratchet over the next 70 adjacent tooth on its forward stroke. When the dog 43 is ratcheting over a tooth of the wheel, the point of pawl 65 will be operative to prevent any retrogressive movement on the wheel. 75

If the cross-head 54 be now adjusted to the position in which it appears in views 7, 8, and 9 of the drawing the transverse pin 69 carried by arm 70 pivoted to the cross-head will be moved forwardly along the side 80 member 26 of the frame. It will be guided with reference to said side member by means of the tension spring 71 which holds it thereagainst. In the course of the forward movement of pin 69 the said pin will ride 85 upon an elevated cam surface of dog 43 and will thereby lift the hook portion 47 of said dog clear of the toothed wheel 37. At the same time the pin 69 will operate with a certain degree of lost motion upon the extremity of a slotted link 72 which controls the position of cam 73. During the lifting operation the said cam 73 was operative, as shown in Figure 10, to force out of the path of pawl 65 the pawl-controlling lever 74 and 90 pin 75 against the tension of spring 76. When, however, the cross-head 54 is moved forwardly to its new position it permits the spring 76 to oscillate lever 74 in a clockwise direction to push cam 73 to the position 95 in which it appears in Figures 8 and 9. The lost motion provided by the slot in link 72 allows the cam 73 to retain this position despite the movement of the slide 34' upon which it is mounted. 100

With the parts as shown in Figure 8 the entire weight or load on element 11 is supported by the pawl 65. As the actuating handle is moved forwardly the dog 43 is imparted a corresponding rearward movement, and its hooked extremity 47 ultimately picks up a tooth of wheel 37, thereby relieving the finger 48' or point of pawl 65. The pin 75 carried by lever 74 will, in the course of this movement, have moved 110 onto the relatively higher cam surface of pawl 65, thereby moving pin 75 out of contact with the lower surface of side member 26 of the frame and placing a resulting additional tension on spring 76. This tension 115 would be adequate to overcome the compression of spring 67 and would oscillate pawl 65 to releasing position if it were not for the fact that the load of wheel 37 keeps the point of the pawl in engagement 120 between two adjacent teeth of the wheel. When, however, the hook 47 picks up a tooth of said wheel and relieves pawl 65 of load, the said pawl springs outwardly as 125 shown in Figure 9. As the actuating han- 130

- dle is again moved rearwardly it permits dog 43 to move forwardly and the wheel 37 is thus allowed to rotate in a clockwise direction to lower the load. The spring 76 5 acting on the cam surface of pawl 65 maintains the point 48' of the pawl retracted until it has cleared the tooth of wheel 37 with which it was previously engaged and is in a position for engagement with the next 10 succeeding tooth. This next succeeding tooth is picked up as the actuating handle moves to a position such that pin 69 depresses the rear end of dog 43, as shown in Figure 8, whereupon the operation is 15 repeated to lower the load supporting element as long as the handle 30 is oscillated or until the last tooth of wheel 37 is reached, or the cross-head 54 is adjusted for upward 20 movement.
- While the construction illustrated in Figures 1 to 6 is very much preferred by me, nevertheless it will be recognized by those skilled in the art that the double and single 25 acting jacks herein disclosed have much in common and each satisfies in some measure the objects of this invention. In this regard the double acting jack obviously comes closest to completely satisfying my purposes since, its use in actual tests has demonstrated the fact that it will act easily to raise 30 greater loads in less time than can be raised with any jack of like type with which I am familiar. This is accomplished due to the fact that I have succeeded in producing in 35 this type of jack a motion transmitting mechanism such that each forward and back stroke of the actuating handle results in movement of the load supporting element.
- I claim:
1. In a device of the character described, 40 the combination with a horizontal frame and an oscillatory handle carried thereby, of a load supporting element vertically movable with reference to a portion of said frame longitudinally spaced from said handle, and motion transmitting connections operative between said handle and said element and adapted to actuate said element in a given direction upon the oscillation of 45 said handle in either direction.
2. In a device of the character described, 50 the combination with a horizontal frame, an oscillatory handle mounted thereon and a vertically movable load supporting element connected with the frame at a point 55 remote from the handle, of motion transmitting connections operative between said handle and said element to actuate said element uni-directionally upon each movement of said handle in either direction, and means for controlling said motion transmitting connections, whereby said connections 60 will selectively actuate said element either upwardly or downwardly.
3. In a device of the character described, 65 the combination with a vertically movable load supporting element, of a rotor journaled adjacent said element upon an axis transverse with respect to the path of movement of the element, and a link pivotally 70 connected with both said rotor and said element, whereby to transmit vertical movement to said element upon the rotation of said rotor.
4. In a device of the character described, 75 the combination with a load supporting element guided for vertical movement, of a link pivotally connected with said element to swing in a plane substantially parallel to the path of said movement and substantially 80 radial with respect to said element, and a toothed wheel journaled for rotation adjacent said element in a plane substantially parallel to said first mentioned plane and having a portion operatively connected piv- 85 otally with said link.
5. In a device of the character described, 90 the combination with a vertically movable load supporting element, of a rotor journaled for operation adjacent said element and provided with a plurality of teeth having their corresponding sides substantially disposed respectively on radii and chords of 95 said rotor, a link operatively connecting said rotor with said element, a slide reciprocable adjacent said rotor, and dogs operatively connected with said slide and positioned for engagement with the said teeth alternately at substantially diametrically opposite sides of said rotor, whereby to transmit 100 rotative motion to said rotor upon the reciprocation of said slide in either direction.
6. In a device of the character described, 105 the combination with a pair of members guided respectively for reciprocal movement substantially at right angles to each other, of a rotor disposed adjacent the point of intersection of the paths of movement of 110 said members, means adapted to transmit motion to said rotor from one of said members to produce uni-directional rotation of said rotor upon the movement of said member in either direction of reciprocation, said rotor being directly connected with the 115 other of said members, whereby the reciprocal movement of the first of said members will result in uni-directional movement of the other of said members.
7. In a device of the character described, 120 the combination with a pair of members guided for independent reciprocation in angularly related paths of movement, of a toothed rotor adjacent the point of intersection of said paths of movement of said 125 members and directly connected with one of said members, and a set of dogs movable with the other of said members and adapted to engage mutually remote teeth on the periphery of said rotor, said dogs being 130

- adapted to produce uni-directional rotation of said rotor upon the reciprocation in either direction of the member with which the dogs are movable.
5. 8. In a device of the character described, the combination with a pair of members guided for independent reciprocation in angularly related paths of movement, of a toothed rotor adjacent the point of intersection of said paths of movement of said members and directly connected with one of said members, and a set of dogs movable with the other of said members and adapted to engage mutually remote teeth on the periphery of said rotor, said dogs being adapted to produce uni-directional rotation of said rotor upon the reciprocation in either direction of the member with which the dogs are movable, and means operative to control said dogs during the reciprocative movement of the member by which they are carried, said means being adapted selectively to control the direction of rotation of said rotor and the consequent direction of reciprocation of the member directly connected therewith.
9. In a device of the character described, the combination with a pair of members reciprocable in angularly related paths, of a toothed wheel disposed adjacent the point of intersection of said paths and directly connected with one of said members, and a dog movable with the other of said members and adapted to interact with the teeth of said wheel to produce rotation thereof.
10. In a device of the character described, the combination with two reciprocable members movable in angularly related paths, of a toothed wheel disposed adjacent the point of intersection between said paths, a link pivoted to said wheel and to one of said members, and a dog connected with the other of said members for movement therewith and adapted for interaction with successive teeth on said wheel.
11. The combination with a frame and a load supporting element suitably guided therein of a rotor adjacent said element and connected therewith, a handle pivotally connected with said frame at a distance from said element and said rotor and oscillatory through an arc above its pivotal connection, and motion transmitting connections between said handle and said rotor, said connections being adapted to produce uni-directional movement of said rotor upon oscillation of the handle in either direction.
12. In a device of the character described, the combination with a vertically reciprocable load supporting element, of a frame providing a guiding channel for said element, an ear projecting laterally from said element, a rotor journalled in said frame adjacent said element and substantially in the plane of movement thereof, and a link comprising spaced members pivotally connected with said ear and said rotor upon either side thereof.
13. In a device of the character described, the combination with the spaced side members of a jack frame, of a transverse shaft supported from said members, a rotor journaled on said shaft, a slide comprising laterally spaced members disposed between said frame members and guided upon said shaft upon either side of said rotor, and dogs pivotally connected between the laterally spaced members of said slide and extended respectively above and below said rotor for interaction therewith.
14. In a device of the character described, the combination with a jack frame and a toothed wheel journaled therein, of a slide guided for reciprocation in said frame, and a pair of dogs adapted respectively for engagement with the teeth on the upper and lower portions of the periphery of said wheel, one of said dogs being provided terminally with a hook member and the other being a compression member adapted to transmit motion to said wheel to cause uni-directional rotation thereof upon movement of said slide in either direction.
15. In a device of the character described, the combination with a jack frame and a toothed wheel journaled therein, of a slide reciprocable longitudinally of said frame to and from said wheel, tension and compression dogs pivotally connected with said slide to move relative thereto and engageable respectively with teeth at spaced portions on the periphery of said wheel, a spring urging the terminal portions of said dogs toward position to engage with said teeth as the slide reciprocates, and means selectively operative in the path of movement of said dogs with the slide to trip said dogs at predetermined points in said path, whereby to permit said wheel to rotate reversely at a predetermined rate during the reciprocation of said slide.
16. In a device of the character described, the combination with a load supporting element and a toothed wheel operatively connected therewith to reciprocate said elements in accordance with the rotation of said wheel, of a slide guided for reciprocation with respect to said wheel, dogs pivotally connected with said slide and having terminal portions formed for engagement with the teeth of said wheel at spaced points on the periphery thereof, a spring urging said terminal portions in the direction of said wheel, a pair of dog-tripping elements manually adjustable to and from operative position with respect to the path of movement of said dogs, and cam means connected with said dogs and adapted for interaction with said elements when said elements are in their said operative position, said cam

being formed to trip said dogs at predetermined points in the reciprocation of said slide. 65

17. In a device of the character described, 5 the combination with a vertically reciprocable load-carrying element and a toothed wheel directly connected therewith, the periphery of said wheel being formed with surfaces disposed substantially on radii and 10 chords of said wheel, of a slide reciprocable with respect to said wheel, a tension dog pivotally connected with said slide and provided with a hook-shaped terminal portion 15 adapted to engage the substantially radial surfaces of successive teeth upon said wheel, a compression dog pivotally connected with said slide and having a terminal portion adapted to enter interdental spaces on said wheel and engage the substantial radial surfaces 20 of said teeth at an angle such as to be retained in said spaces when under load, spring means urging the said terminal portions of said dogs into the interdental spaces of the wheel, cam means connected with 25 each of said dogs and provided with a cam surface of predetermined contour and a pin adjustably guided with respect to the path of movement of said slide to and from an operative position for interaction with the 30 cam means connected with one of said dogs, said pin being adapted, when in its operative position to interact with said cam means and, at predetermined points in the movement of said slide, to overcome said 35 spring means to lift the said terminal portion of said last mentioned dog from interdental spaces of said wheel. 100

18. In a device of the character described, the combination with a wheel having teeth 40 provided respectively with surfaces disposed substantially on radii and chords of said wheel, of a slide guided for reciprocatory movement with respect to said wheel, a dog pivotally connected with said slide and provided with a terminal portion adapted to enter interdental spaces of said wheel and to engage the substantially radial faces of successive teeth thereon, said teeth being formed to retain said dog in said spaces 45 when said dog is under pressure, a spring urging said dog toward said wheel, a cam connected with said dog, a cam follower guided for adjustment to and from an operative position for interaction with said 50 cam and mounted for resilient yielding from said position in opposition to a pressure exceeding that of said spring, said cam surface and cam follower being adapted for interaction in predetermined positions of 55 movement of said slide to subject said dog to a force tending to withdraw it from the interdental spaces of said wheel, whereby said dog will disengage itself from said wheel when relieved of load and will not 60 again engage said wheel during the said interaction of said cam and cam follower. 65

19. In a device of the character described, the combination with a load-supporting element guided for vertical reciprocation, of a toothed wheel journaled for rotation adjacent said element and provided with a link connection therewith and a slide reciprocable with reference to the wheel and provided with tension and compression members formed respectively for interaction 75 with teeth on the upper and lower peripheral portions of said wheel. 70

20. In a device of the character described, the combination with a load supporting element guided for vertical reciprocation, of 80 a toothed wheel adjacent said element and linked thereto, a slide reciprocable with reference to said wheel, closely adjacent pivot pins mounted in said slide, dogs fulcrumed respectively on said pins and formed to 85 extend arcuately about said wheel at substantially diametrically opposite points thereon, one of said dogs comprising a compression member and the other of said dogs being provided with a hook and comprising 90 a tension member, spring means urging said dogs to operative engagement with said wheel, a cross-head adjustable substantially in the path of movement of said slide, arms pivoted to the cross-head and provided with 95 pins adapted in one position of the cross-head to project in the path of movement of portions of said dogs, said portions being provided with cam surfaces adapted for interaction with said pins, means for normally guiding said pins to define a minimum separation therefor, spring means normally maintaining said pins in operative contact with said guiding means and adapted to exert thereon a force greater than that 100 exerted by the spring means acting on the dogs and transmitted through said cam surfaces to said pins, said cam surfaces being formed to interact with said pins at predetermined points in the movement of said slide when said cross-head is adjusted to the said operative position whereby to selectively lift said dogs from engagement with said wheel to permit the backward rotation thereof. 110 115

21. In a device of the character described, the combination with a toothed wheel and a slide reciprocable with reference thereto, of a dog pivotally connected with said slide and movable therewith and adapted for interaction with the teeth of said wheel, a cam member connected with the dog, a cam-follower mounting adjustable between operative and retracted positions, a cam follower yieldably supported from said mounting 120 and adapted, when said mounting is in its operative position, to engage operatively the cam surface on said dog at a predeter- 125

mined point in the movement of said dog with said slide, a spring normally pressing said dog toward said wheel, and a spring opposing the yielding movement of said cam follower and adapted normally to overcome the force of said first mentioned spring, the teeth of said wheel being formed to retain said dog under load whereby to prevent the dog from yielding under the pressure of said last mentioned springs until the load on said dog is relieved following the period of said interaction.

22. In a device of the character described, a load supporting element comprising a member guided for reciprocation and provided with a central opening, a plunger adjustable axially and rotatable in said opening and provided with peripheral grooves and a latch member slidable transversely of said first mentioned member and adapted for engagement with one of the grooves of said plunger.

23. In a device of the character described, a work supporting element comprising in combination a pair of telescopically adjustable members adapted for relative reciprocation and rotation, the innermost of said members being peripherally grooved at axially spaced intervals, and a latch device supported from the outer of said members and adjustable transversely thereof, said latch device being receivable in the grooves of the innermost member and being provided with an arcuate notch adapted to receive the central portion of said member for the support thereof from the outermost member

while permitting relative rotation between said members.

24. In a device of the character described, the combination with a horizontal frame providing a rectilinear guideway and an oscillatory handle in pivotal connection with said frame at a point remote from said guideway, of a handle operated load supporting element vertically movable in said guideway, and motion transmitting connections operative between said handle and said element and adapted to actuate said element in a given direction upon the oscillation of said handle in either direction. 50

25. In a device of the character described, the combination with a horizontal frame providing a rectilinear upright guideway and an oscillatory handle in pivotal connection with said frame at a point remote from 55 said guideway, of a handle operated load supporting element reciprocable in said guideway, motion transmitting connections operative between said handle and said element including a toothed member connected with said element and a pair of pawls connected with said handle adapted upon oscillation of said handle in opposite directions to interact respectively with said toothed member to produce unidirectional movement of said element, and means for controlling said motion transmitting connections whereby selectively to actuate said element either upwardly or downwardly in 60 said guideway. 65
